UNITED STATES PATENT OFFICE.

HARRY W. HERMAN, OF CLEVELAND, OHIO.

VALVE-OPERATING MECHANISM.

1,427,385.

Specification of Letters Patent. Patented Aug. 29, 1922.

Application filed March 2, 1920, Serial No. 362,765. Renewed February 16, 1922. Serial No. 537,122.

To all whom it may concern:

Be it known that I, HARRY W. HERMAN, a citizen of the United States of America, residing at Cleveland, in the county of 5 Cuyahoga and State of Ohio, have invented certain new and useful Improvements in Valve-Operating Mechanisms, of which the following is a specification.

This invention relates to certain new and 10 useful improvements in valve operating mechanisms for the inlet or exhaust valves of internal combustion engines or the like.

The primary object of the invention is to 15 provide an improved valve operating mechanism by means of which a gradual and positive opening of the valve is secured, free from jerks and jars and noiseless in action.

A further object of the invention is to 20 provide a substantially noiseless valve operating mechanism which is of such construction as to automatically compensate for wear which inevitable takes place at the various connections between the members of the valve operating mechanism, means 25 being also provided whereby manual adjustment may be made for insuring opening and closing of the valve at the proper times even though such wear takes place.

The invention consists of the features of 30 construction, combination and arrangement of parts hereinafter fully described and claimed, reference being had to the accompanying drawing in which the figure is a view partly in vertical section and partly 35 in side elevation of the major portion of an internal combustion engine having a valve operating mechanism constructed in accordance with the present invention.

Referring more in detail to the drawing, 40 the present invention contemplates an improved valve operating mechanism for internal combustion engines of that type which usually embody a cylinder 5 having a piston 6 reciprocable therein which is 45 operatively connected by a piston rod 7 with a crank shaft 8 whereby, when said piston is reciprocated, rotation is imparted to said crank shaft. The engine also embodies the usual shaft 9 which is provided 50 with a cam 10 engaging the roller 11 upon the lower end of the push rod or pitman 12 for raising the latter upon rotation of the shaft 9, said shaft 9 being geared to the crank shaft 8 in the usual or any preferred 55 manner so as to obtain rotation of said cam shaft 9. The upper end of the cylinder 5

is provided with the usual seat 13 for the valve 14 which is normally held against said seat in the usual manner by means of a spring 15 which encircles the stem 16 of 60 the valve 14 and bears at one end upon the top of the cylinder 5 and at its other end against the washer or similar device 17 which is fastened upon the outer end portion of the stem 16. A bracket 18 is carried 65 upon the head of the cylinder 5, and a rocker arm or operating lever 19 is pivoted upon the upper end of this bracket intermediate its ends as at 20, one end of said rocker arm 19 being engaged as at 21 with 70 the upper end of the valve stem 16 in the usual way and the other end of said rocker arm 19 being operatively connected to the push rod 12 so that when the cam shaft 9 is rotated the valve 14 is moved to and from 75 its seat in the well known manner. The construction so far described is substantially that which is commonly used in internal combustion engines in use at the present time. 80

The present invention contemplates the threading of the upper end of the push rod 12 as at 22 for a material distance for screw threaded reception of the locking nut 23 and the nut 24 which is superimposed thereon, said nut 24 being provided with an upstanding rigid sleeve 25 surrounded at its base with an annular enlargement 26 which provides a shoulder 27 adapted to function as will presently become apparent. An inverted cup 28 snugly telescopes onto the sleeve 25 and is of such length as to have its lower edge lie slightly spaced above the shoulder 27, the parts being normally yieldingly retained in this relation by means of 95 a helical compression spring 29 or other equivalent compression member which is arranged within the sleeve 25 and bears at one end against the end wall of the cup 28 and at its other end upon the top of the 100 nut 24 which carries the sleeve 25. A member such as a ball 30 is rigid upon the upper end of the cup 28 and is engaged with the adjacent end of the rocker arm 19 to provide a pivotal connection at this point, the ball 30 being indicated as cooperating with a socket 31 formed in the adjacent end of the rocker 19. Obviously, the spring 29 is of less strength than the spring 15 which seats the valve 14. 110

In operation, the engine is started in the usual manner to obtain rotation of the cam

shaft 9. With the parts disposed in their normal positions as shown in the drawing, the cam 10 moves around and causes upward movement of the push rod 12 and the 5 nut 24 together with its sleeve 25, whereupon the spring 29 is compressed for gradually allowing the shoulder 29 to come into engagement with the lower edge of the cup 28. The cup 28 is then forced upwardly so 10 as to rock the arm 19 upon its pivot and to force the stem 16 downwardly against the action of the spring 15 so as to unseat the valve 14. When the cam 10 moves past the roller 11 the spring 15 is allowed to gradually 15 raise the stem 16 so as to reseat the valve 14 and return the rocker arm 19, cup 28, sleeve 25 and push rod 12 to their normal positions and relationship. This provides an easy, gradual and uniform valve opening motion. 20 free from shocks, jerks and jars, and preventing the valve from chattering on its seat as well as taking up all ordinary lost motion due to wear.

From the above it will be seen that the 25 spring 29 insures engagement at all times between the roller 11 and cam 10, between the ball 30 and the adjacent end of the rocker arm 19 and between the stem 16 and the other end of said rocker arm. Should 30 wear take place at any of these points the spring 29 will automatically separate the members 26 and 28 so as to compensate for this wear and maintain the above mentioned contact, while the nut 24 may be screwed 35 outwardly of the rod 12 to the desired adjustment and there retained by the lock nut 23 so as to maintain at all times the same relationship between the shoulder 27 and the lower edge of the cup 28 for insuring at all 40 times opening and closing of the valve 14 exactly when proper.

From the foregoing description, it is believed that the construction and operation as well as the advantages of the present invention will be readily understood by those 45 skilled in the art.

Minor changes may be made without departing from the spirit and scope of the invention as claimed.

50 It is to be understood that a rubber or sheet metal member may be easily employed to perform the function of the spring 29, and it is therefore desired that the terms of the claims be construed sufficiently 55 broadly to have such interpretation placed upon the same.

What I claim as new is:—

1. In a valve operating mechanism for engines, a slidably mounted push rod, an operating cam for said push rod, a pivotally mounted operating lever, a spring seated valve having a slidably mounted stem pivotally associated with one end of said operating lever, an inverted cup pivotally associated with the other end of said operating

lever, a sleeve adjustable longitudinally on one end of said push rod and snugly slidably telescoped into said cup, and a compression spring within said sleeve yieldingly maintaining constant contact between the 70 push rod and its said operating cam.

2. In a valve operating mechanism for engines, a slidably mounted push rod, an operating cam for said push rod, a pivotally mounted operating lever, a spring seated 75 valve having a slidably mounted stem pivotally associated with one end of said operating lever, an inverted cup pivotally associated with the other end of said operating lever, a nut adjustable longitudinally on one 80 end of said push rod and having a coaxially rigid sleeve thereon snugly slidably telescoped into said cup, a compression spring within said sleeve yieldingly maintaining constant contact between the push rod and 85 its said operating cam, and an external shoulder on said nut arranged to engage the lower edge of said cup upon compression of said spring and predetermined movement of the sleeve into the cup, whereby the valve 90 will be positively opened.

3. In a valve operating mechanism for engines, a push rod, an operating cam therefor, a pivotally mounted operating lever, a spring seated valve having a stem, one end 95 of said lever having contact pivotal connection with said valve stem, an inverted cup having contact pivotal connection with the other end of said lever, a sleeve adjustable longitudinally of one end of said push rod 100 and snugly slidably telescoped with said cup, and a compression spring within said sleeve yieldingly maintaining constant contact between the valve stem and the operating lever, between the operating lever and 105 the cup, and between the push rod and its said operating cam.

4. In a valve operating mechanism for engines, a push rod, an operating cam therefor, a pivotally mounted operating lever, a spring seated valve having a stem, one end of said lever having contact pivotal connection with said valve stem, an inverted cup having contact pivotal connection with the other end of said lever, a sleeve adjustable longitudinally 110 of one end of said push rod and snugly slidably telescoped with said cup, a compression spring within said sleeve yieldingly maintaining constant contact between the valve stem and the operating lever, between the operating lever and the cup, and between the push rod and its said operating cam, and means to limit movement of the cup and the sleeve one within the other upon compression of said spring, whereby the valve will be 115 positively opened.

5. In a valve operating mechanism for engines, a push rod, an operating cam therefor, a pivotally mounted operating lever, a spring seated valve having a stem, one end 120

130

of said lever having contact pivotal connection with said valve stem, a member having contact pivotal connection with the other end of said lever, a second member adjustable longitudinally of one end of said push rod, a compression spring between said members yieldingly maintaining constant contact between the valve stem and the operating lever, between the operating lever and the first named member, and between the push rod and its said operating cam, and means to limit movement of said members toward each other upon compression of said spring, whereby the valve will be positively opened.

6. In a valve operating mechanism for engines, a push rod, an operating cam there-

for, a pivotally mounted operating lever, a spring seated valve having a stem, one end of said lever having pivotal connection with 20 said valve stem, an inverted cup having pivotal connection with the other end of said lever, a sleeve adjustable longitudinally of one end of said push rod and snugly slidably telescoped with said cup, a compression 25 spring within said sleeve yieldingly maintaining constant contact between the push rod and its said operating cam, and means to limit movement of the cup and the sleeve one within the other upon compression of 30 said spring, whereby the valve will be positively opened.

In testimony whereof I affix my signature.
HARRY W. HERMAN.
